UNITED STATES PATENT OFFICE.

ACALLIOUS ELBERT SHUTTERLY, OF INDIANAPOLIS, INDIANA, ASSIGNOR TO THOMPSON'S MALTED FOOD COMPANY, OF WAUKESHA, WISCONSIN, A CORPORATION OF WISCONSIN.

MALTED-MILK DISPENSER.

1,355,279.

Specification of Letters Patent.

Patented Oct. 12, 1920.

Application filed September 9, 1918. Serial No. 253,219.

To all whom it may concern:

Be it known that I, ACALLIOUS ELBERT SHUTTERLY, a citizen of the United States, and resident of Indianapolis, in the county 5 of Marion and State of Indiana, have invented new and useful Improvements in Malted-Milk Dispensers, of which the following is a description, reference being had to the accompanying drawings, which are a 10 part of this specification.

This invention has for its object to provide a dispenser of malted milk or similar products, for use at soda fountains or the like, which will serve to protect the material 15 from moisture in the air and will discharge it in measured quantities and at the same time agitate the material in the container to assist the free flow thereof.

With the above and other objects in view, 20 the invention consists in the malted milk dispenser as herein claimed and all equivalents.

Referring to the accompanying drawings, in which like characters of reference indicate 25 the same parts in different views:

Figure 1 is a side view of a malted milk dispenser constructed in accordance with this invention;

Fig. 2 is a sectional view thereof; and, 30 Fig. 3 is a detail view partly in section showing the arrangement of the agitator.

In these drawings 10 indicates a supporting bracket having a clamp 11 at its lower end for securing it to the edge of a table 35 or counter and provided with an overhanging cup-shaped jar-holder 12 at its upper end.

A glass jar 13 containing the malted milk or other granular material which it is desired to dispense, is held in an inverted position in the jar-holder 12 and is preferably clamped by means of oppositely positioned set screws 14 engaging above the flange of the jar.

In the bottom of the jar container 12 is an opening 15 through which the material may flow into a measuring cavity 16 formed in a cylindrical plug 17 which is rotatably mounted in a cylindrical bearing 18 secured 50 to or projecting from the bottom of the jar-holder. A crank handle 19 projecting from the plug 17 constitutes a means for giving

the plug a half turn to move it from the position in which its cavity 16 registers with opening 15 to the opposite position in which the cavity 16 registers with an opening 20 in the bottom of the bearing 18. Thus the material received by the cavity 16 from the container 13 through the opening 15 in one position of the plug is discharged through 60 the opening 20 into a glass held therebeneath when the plug is turned to its other position.

To limit the crank handle to a swing of one-half turn, a lug 21 is formed on the end of the plug 17 and engages opposite shoulders 22 projecting from the bearing 18. This projecting lug 21 also serves to prevent endwise movement of the plug in one direction while endwise movement of the plug in the opposite direction is prevented by means of 70 a screw 23 threaded in the end of the plug with its head engaging the edge of the bearing 18. The screw 23 has one side of its head cut away so that it is not necessary to entirely remove it in order to release the 75 plug to permit of its withdrawal.

An agitator 24, preferably consisting of a bent wire, is passed through a flaring opening 25 in the bottom of the jar holder 12 near the end of the plug and its bent crank-like end enters an opening in the end of the plug which is at one side of the center. The turning of the plug thus causes the agitator to slide through the opening and swing from one side to the other so as to carry its V-shaped other end back and forth above the opening 15 to agitate the material directly above said opening.

In operation the glass is held beneath the dispenser and the handle 19 is swung from one position to the other, causing the measured quantity of material in the cavity 16 to be dropped into the glass. The handle is then returned to its original position where the cavity is refilled with the material which has been loosened by the swinging movements of the agitator incident to the movements of the plug.

The plug may be readily removed so that the parts may be kept clean. The material is protected from the air keeping it free from dust and preventing caking from the moisture in the air.

I desire it to be understood that this in-

vention is not limited to any specific form or arrangement of parts except in so far as such limitation is specified in the claims.

What I claim as new and desire to secure by Letters Patent is:

- 5 1. A dispenser for malted milk and the like, comprising a container having an opening in its bottom, a plug turning in a bearing in the bottom of the container and provided with a cavity to receive material from the container through said opening and adapted when the plug is turned to discharge the material through an opening in the bearing, and an agitator passing through 10 an opening in the bottom of the container and having eccentric connection with the plug to be swung above the opening by the turning movements of the plug.
- 15 2. A dispenser for malted milk and the like, comprising a suitably supported jar-holder, an inverted jar held thereby, a plug mounted to turn in a bearing in the bottom of the jar-holder and provided with a cavity registering with a discharge opening in the 20 bottom of the jar-holder, a handle on the plug for turning it to a position in which the cavity registers with an opening in the bearing, a wire passing through an opening in the jar holder and having eccentric 25 connection with the plug at one end and having the other end bent over the discharge 30

opening of the jar-holder for agitating the material.

3. A dispenser for malted milk and the like, comprising a supporting bracket having a clamp at one end and an overhanging cup-shaped jar-holder at the other end, an inverted jar supported in the jar-holder, a cylindrical bearing on the bottom of the jar-holder, a plug mounted to turn within the bearing and provided with a cavity registering with a discharge opening through the jar-holder, a crank handle on the plug for turning it to cause the cavity to register with an opening in the bearing, a lug on the plug 35 engaging shoulders on the bearing for limiting the movements of the plug, a screw threaded in the end of the plug with its head engaging the bearing to prevent the withdrawal of the plug, and an agitator formed 40 of wire passing through an opening in the jar holder with one end bent to enter an eccentric opening in the end of the plug and the other end extending over the discharge 45 opening of the jar-holder.

In testimony whereof I affix my signature, in presence of two witnesses.

ACALLIUS ELBERT SHUTTERLY.
